UNITED STATES PATENT OFFICE

PINK T. BYNUM, OF CALLIHAM, TEXAS

BENDING AND STRAIGHTENING DEVICE

Application filed May 29, 1931. Serial No. 541,074.

This invention relates to bending and straightening devices adapted to straighten a frame or axle on a motor vehicle without removing the fenders, running boards or 5 motor from the chassis, as well as to straighten twisted and bent axles without removing the same from the auto or truck.

A further object of the invention is to provide a device which may be used to 10 straighten bends or remove warps or twists from various metal elements, such as axles, shafts, crank shafts, angle irons, channel and bar steel, and pipe.

A further object is to provide a device including a stress bar which may be placed 15 longitudinally of the member to be straightened and is equipped with a yoke which carries a post and jack screw, the stress bar being of such construction as to be strong and 20 rigid and permit of the yoke being extended in various directions from the bar to accommodate the bar to the work which must be performed.

A still further object is to provide a 25 straightening device in which the post carrying the jack screw is adjustably secured in the legs thereof so that it can be moved toward or away from the stress bar to accommodate the device to various applications to 30 straighten a bent metal member.

With the above and other objects in view the invention consists in certain novel details of construction and combinations of 35 parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a perspective view of a pair of bending and straightening devices in position to straighten a chassis frame,

Fig. 2 is a vertical sectional view through the device in applied position,

Fig. 3 is a plan view of a plurality of the devices applied alternately to opposite sides 50 of the work, and

Fig. 4 is a fragmentary perspective view showing a curved stress bar.

Referring now to the drawings in which like characters of reference designate similar parts in the various views, 10 designates a 55 channel iron chassis frame member to which my invention is applied for the purpose of illustration.

In carrying out the invention, I provide a stress bar 11 which preferably is hollow and 60 preferably is also rectangular in cross section to provide a plurality of faces disposed at an angle to each other. The stress bar is preferably formed of metal and may be either straight longitudinally, as shown in 65 Fig. 1, or curved longitudinally, as shown at 12 in Fig. 4.

Mounted on the stress bar is a yoke 13 which preferably is U-shaped in contour and 70 may be formed of any suitable strap metal. In the present embodiment of the invention, the yoke embraces three sides of the rectangular stress bar, and the legs 14 of the yoke project beyond the fourth side of the bar and, 75 consequently, extend outwardly from the same side of the stress bar. The yoke may be disposed on the stress bar to extend laterally therefrom or upwardly or downwardly, these four positions of the yoke permitting of application of the device to various 80 types of work to be performed.

A substantially rectangular solid post 15 is loosely fitted in correspondingly shaped openings 16 formed in the legs of the yoke. The post extends perpendicular to the legs 85 and may be slid upwardly or downwardly in said openings. Each leg is equipped with a lug 17 and a set screw 18 which passes through the lug, both lugs extending perpendicular to the legs. The set screws 18 90 may be adjusted as desired to hold the post snugly against the inner edges 19 of the openings 16 and maintain the post at any adjusted position therein, as will be understood.

The post is equipped with a jack screw 20 which extends parallel to the legs of the yoke and is adapted to be forced against the member 10 to be straightened.

In practice, three such devices are used, 100

turned in opposite directions on the stress bar 11, as best shown in Fig. 3, with the posts 15 disposed on alternate sides of the member 10 to be straightened. Thus, the jack screws 5 20 oppose each other and, during uniform tightening of the jack screws, the member 10 will be easily and quickly straightened.

It will be observed that the yokes 13 may be adjusted longitudinally of the straight 10 stress bar 11 or curved stress bar 12, as the case may be, and that the post 15 may be adjusted vertically in the yoke to any desired position.

In general, it may be said that the part or 15 member to be bent, straightened or twisted may be placed longitudinally of or parallel with the stress bar and between the jack screws of the posts, and that the jack screws may be adjusted to bear on whatever part of 20 the work it is desired to straighten.

To remove twists, it is found desirable to use four of the bending and straightening devices, one pair being used to reverse the strain of the other pair.

25 From the above description, it is thought that the construction and operation of my invention will be fully understood without further explanation.

Having thus described the invention, I 30 claim:

1. A bending and straightening device including a stress bar adapted to be disposed longitudinally of the member to be straightened, a yoke embracing the bar and having 35 the legs projecting from the same side of the bar; a post adjustably mounted in the legs of the yoke and extending perpendicular to said legs, and a jack screw for engaging said member and carried by the post parallel to said 40 legs.

2. A bending and straightening device including a stress bar having outer faces disposed at an angle with respect to each other, a yoke adapted to be disposed to embrace 45 the bar and bear upon said faces, the angular inclination of the faces permitting of the yoke being disposed to extend in various directions from the bar, a post adjustably mounted on the legs of the yoke and extending 50 perpendicular to said legs, and a jack screw carried by said post.

3. A bending and straightening device including a hollow rectangular stress bar, a substantially U-shaped yoke embracing the 55 bar and having the legs projecting beyond the same side of the bar, a post carried by the legs of the yoke and extending perpendicular to said legs, and a jack screw carried by the post.

60 4. A bending and straightening device including a stress bar, a yoke embracing the bar and having the legs projecting from the same side of the bar, said legs having aligned 65 openings therein, a post slidably fitted in said openings and extending perpendicular to the

legs, means for adjustably securing said post in said openings, and a jack screw carried by said post.

5. A bending and straightening device comprising a stress bar, yoke adapted to embrace the stress bar and having the legs extending from the same side thereof, said legs having openings therein, lugs on the legs at the outer edges of said openings, set screws carried by said lugs, a post slidably mounted 70 in said openings and clamped in adjusted positions against the inner edges of said openings by said set screws, and a jack screw carried by said post.

In testimony whereof I affix my signature. 80
